ATTORNEY

For Admiration,

WITNESS:

UNITED STATES PATENT OFFICE.

ARTHUR E. SOCIN AND GEORGE B. IRVINE, OF BUCYRUS, OHIO.

DESIGN FOR A LENS FOR VEHICLE LAMPS.

Application filed February 20, 1922. Serial No. 777. Term of patent 7 years.

To all whom it may concern:

Be it known that we ARTHUR E. SOCIN and GEORGE B. IRVINE, citizens of the United States of America, residing at Bucyrus, in the county of Crawford and State of Ohio, have invented a new original, and ornamental Design for a Lens for Vehicle Lamps, of which the following is a specification, reference being had to the accompanying drawings, forming a part hereof.

Figure 1 is a front face view.

Figure 2 is a rear face view.

Figure 3 is a vertical section.

We claim:

The ornamental design for a lens for vehicle lamps as shown.

ARTHUR E. SOCIN.
GEO. B. IRVINE.

Witnesses:

GODFREY LENTHOLD,
C. A. LENTHOLD.
